ELECTROLYTIC CELL

Dwight R. Means, Wadsworth, Ohio, assignor to
Hooker Electrochemical Company, Niagara
Falls, N. Y., a corporation of New York

Application June 25, 1940, Serial No. 342,308

1 Claim. (Cl. 204—266)

This invention relates to an improved electrolytic cell for use in the electrolysis of alkali metal chloride solutions and the preparation of chlorine and alkali metal hydroxide. In accordance with the present invention, I have been able to devise a novel electrolytic cell structure of improved and simplified construction. This cell is found to operate more efficiently and to have a capacity substantially higher per unit of floor space occupied than other electrolytic cells now in commercial use.

The invention will be more fully understood by reference to the accompanying drawings wherein

Fig. 1 is a plan view of a preferred form of my cell with a portion of the cover being broken away to reveal the cell interior.

Fig. 2 is a vertical sectional view on line A—A of Fig. 1.

Fig. 3 is a vertical sectional view on line B—B of Fig. 1.

Fig. 4 is a view of a modified form of anode assembly which may be constructed in accordance with my invention.

Fig. 5 is a vertical sectional view of the cathode assembly and,

Fig. 6 is a detailed view upon an enlarged scale of a portion of the cathode assembly.

It will be noted that the electrolytic cell comprises an anode assembly 1, which rests upon suitable insulating supports 4, a cathode assembly 2, resting upon the anode assembly, and a suitable cover 3, resting upon the cathode 3, the several assemblages being clamped together in order to form a unitary structure.

In accordance with one modification, the assembly structure comprises a suitable metallic base member 11, upon which spaced banks or rows of anode members 12, of suitable construction are mounted in an upright position. These anodes may comprise slabs or rods or other conveniently shaped electrode and may be constructed of carbon, in the known manner, if desired, or may be constructed of other materials as hereinafter more fully set forth. Various means may be provided for mounting the anode upon base 11. In accordance with one modification, the lower end of the anode slab may be tapered slightly and may be driven into suitably constructed slots or holes in the base member, or the anode may be mounted by means of threaded screws or other supporting means capable of establishing an electrical contact between base 11 and the anode members. Alternatively, the holes or sockets in which the cathodes are inserted may be provided with metallic sleeves of a relatively soft, chemical-

ly resistant metal, such as silver or lead in which the anodes are driven. If the carbon becomes attacked during operation, these sleeves may then be replaced by others having a smaller internal diameter, thus permitting a firm support of the anodes. As a support for the cathode member, annular ring 14, of suitable material is placed upon the periphery of the anode base member. This ring may be of any suitable rigid material, such as rubber-covered metal, resins, etc. In order to insulate the base member from the electrolyte, the base ordinarily is covered with some insulating material, such as bitumen or putty 13.

The cathode structure comprises a main frame 15, 2, of box-like construction which is provided with a pair of chambers 21, at two opposed ends thereof, and a plurality of hollow perforated cathode members 21, of elongated construction extending across the cell and communicating at each end 20 thereof with the chambers 21. These cathode members are generally constructed of metal screen or other suitable foraminous metallic material and are of elongated cross section, being mounted vertically between the banks of vertically extending anodes, as shown in Figs. 1 and 2. These perforated members are covered by suitably formed diaphragms of fibrous materials such as may be obtained by wrapping asbestos paper or other similar product around the members and 25 fastening with adhesive or other convenient means. The upper and lower edges of the cathode main frame and the imperforate area between the cathode members may be provided with an insulating coating 23, in order to avoid 30 possible short-circuiting of the cell and also to prevent generation of caustic adjacent imperforate portions of the cathode. Chambers 21 are provided with one or more outlets for hydrogen 35, and for caustic liquor 26.

40 The cover member 3, which rests upon the cathode structure may be of any convenient construction which is adapted to the collection of chlorine and the introduction of fresh electrolyte. As shown in Figs. 1 and 2, the cover is provided 45 with suitable brine inlets 31, 32 and 34, and an electrolyte manometer connection 36, for indication of the liquor level. Chlorine evolved in the electrolyte rises to the top of the cell and is removed through outlet 33. Gaskets or other sealing means 16, are generally provided between the anode and cathode assemblies and between the cover and the cathode assembly in order to prevent leakage of electrolyte from the cell. The cover and anode and cathode assemblies are 50 clamped firmly together by convenient means 55

(not shown) in a manner similar to that shown in U. S. Patent 1,866,065, granted to K. E. Stuart.

In the normal operation of this cell, the cell is filled with a solution of sodium chloride approximately to the level just above connection 36, and a suitable potential difference is applied between anode base 11, and cathode shell. The brine solution is moved into contact with perforated cathode members 21, and flows more or less continuously therethrough, resulting in the production of sodium hydroxide and hydrogen. The solution thus formed flows through outlets 22 and 28 into chamber 27, where it is collected. The hydrogen formed rises to the top of cathode chambers 27, and is withdrawn through outlet 25. Chlorine is evolved adjacent the anodes and rises to the surface of the electrolyte where it is collected and withdrawn at 33. The caustic solution is removed from the cell through outlets 26.

In accordance with a further modification, it is possible to use a modified form of anode structure, such as may be illustrated in Fig. 4. In accordance with this modification, I may provide a suitable metallic base member 40, which may be of any desired conductive material, but preferably is of copper. In order to prevent attack of the copper by the electrolyte within the cell, the copper is provided with a thin sheath of platinum 41. Wires, sheets or perforated wire gauze anodes 42 may be mounted vertically upon the anode base, and in general, it is found desirable to construct these anodes of similarly cladded material. Thus, these anodes may comprise sheets, wires, or metallic gauze made from copper or copper alloys, cladded with platinum or similar resistant material. This protective sheath may be applied to the base copper by any means which is effective for the purposes, such as electroplating, or by other means. In accordance with one suitable modification, it is

found desirable to weld or otherwise attach thin platinum foils upon the surface of the anode members as is understood in the art of cladding metal sheets. It is found that a cell of the construction above-indicated is considerably superior to other cells of similar structure, having unusually high efficiencies. In addition, it has been noted that higher current densities may be used and that the life of the anodes is appreciably longer than that of anodes in other electrolytic cells of this type.

Although the present invention has been described and claimed with reference to the specific details of certain embodiments thereof, it is not intended that such details shall be regarded as limitations upon the scope of the invention, except insofar as included in the accompanying claim.

I claim:

20 An electrolytic cell comprising an anode assembly consisting of a flat metallic plate horizontally disposed as a conductive base member and having a plurality of recesses and rows of anode plates fitting in said recesses in said base plate so as to be in electrical contact therewith, each row of anode plates extending continuously across from one side of the cell to the other, a cathode assembly insulated from and supported by said base plate and including a peripheral 25 frame having hollow chambers constituting the side walls of the cell and a plurality of hollow foraminous cathode members extending continuously and completely across the cell between said anode plates and opening at each end into 30 the corresponding side chamber of the cathode assembly, and upper and lower outlet means permitting outflow of gases and liquids respectively from said chambers and from end to end of said hollow cathode members.

DWIGHT R. MEANS.
